United States Patent Office

Des. 205,022
Patented June 7, 1966

205,022

WRITING INSTRUMENT

Walter Russell Boss, North Kingstown, R.I., assignor to
A. T. Cross Company, a corporation of Rhode Island

Filed May 13, 1965, Ser. No. 85,269

Term of patent 14 years

(Cl. D74—17)

FIG. 1

FIG. 3

FIG. 1 is a side elevational view of a writing instrument embodying my new design;

FIG. 2 is an enlarged top end view; and

FIG. 3 is an enlarged bottom end view.

I claim:

The ornamental design for a writing instrument, substantially as shown.
